MOBILE GRINDING MILL

Harold S. Shannon, Grosse Pointe Woods, Mich.,
assignor to Mead Mill Company, a corporation
of Michigan

Application April 8, 1952, Serial No. 19,232

Term of patent 14 years

(Cl. D55—1)

To all whom it may concern:

Be it known that I, Harold S. Shannon, a citizen of the United States of America, residing at Grosse Pointe Woods, in the county of Wayne and State of Michigan, have invented a new, original, and ornamental Design for a Mobile Grinding Mill, of which the following is a specification, reference being had to the accompanying drawings, forming a part hereof.

Figure 1 is a top plan view of a mobile grinding mill embodying my new design;

Figure 2 is an elevational view of one side of the mill;

Figure 3 is an elevational view of the rear of the mill;

Figure 4 is an elevational view of the other side of the mill; and

Figure 5 is a view in elevation of the front of the mill.

I claim:

The ornamental design for a mobile grinding mill, as shown.

HAROLD S. SHANNON.
